ATTORNEYS

UNITED STATES PATENT OFFICE

JOHN M. HOTHERSALL, OF BROOKLYN, NEW YORK, ASSIGNOR TO AMERICAN CAN COMPANY, OF NEW YORK, N. Y., A CORPORATION OF NEW JERSEY

CONTAINER

Application filed September 26, 1927. Serial No. 222,005.

This invention relates in general to a container made of sheet metal, and has more particular reference to a double resilient container described as particularly adapted for shipping, storing, transporting and protecting watch movements, although capable of more general use wherever applicable.

In handling and shipping certain products it is necessary not only to protect them from actual contact and resulting damage, but also to cushion them from the shocks of ordinary handling during the course of commercial preparation and delivery for sale. This is particularly true of a delicate mechanism such as watch movements, which should be cushioned against sudden jars or jolts in order to deliver them in the best possible condition.

An important object of the invention is the provision of a double container, in which the inner receptacle is yieldingly engaged by the outer receptacle and the outer receptacle held tightly closed.

A further object of the invention is in the provision of cooperating projections and depressions in the corresponding parts of the containers to permit a resisted, rotative and tilting movement of the inner receptacle.

A still further object of the invention is the provision of a yielding double container of sheet metal, in which the sides give their maximum yielding effect to the article held by interengagement only at their centers, the edges of the inner container gripping the article, and the edges of the outer container being interengaged for holding all the parts together.

Numerous other objects and advantages of the invention will be apparent as it is better understood from the following description, which, taken in connection with the accompanying drawings, discloses a preferred embodiment thereof.

In the drawings:

Figure 1 is a side elevation, with parts broken away, and shown in section, of a container for a watch movement constructed in accordance with the principles of this invention; and

Fig. 2 is a top view of such a container.

Referring more particularly to the drawings, the container of this invention comprises an outer receptacle having telescoping top and bottom parts 5 and 6, and an inner telescoping receptacle comprising top and bottom 7 and 8.

Both receptacles are preferably formed of sheet metal properly drawn and shaped, the outer receptacle parts having their side walls or flanges formed with strengthening beads 9 and having cooperating projections 10 and depressions 11 in the side edges to form a tightening bayonet joint, the inner portions of the depressions 11 being inclined toward the edge of the bottom part 6 to draw the receptacle parts tightly together.

The bottom part of the inner receptacle is properly sized to receive a face plate or projecting edge 12 of a watch movement 13, which preferably rests upon the edge thereof, and the top 7 is formed with an inclined portion 14 about its edge adapted to engage the opposite side of the face plate 12 and to hold it against the edge of the bottom 8. The edges of the top and bottom are formed with cooperating slots 15 and 16 for permitting a watch stem to extend therethrough.

In order to yieldingly hold the top and bottom of the inner receptacle in telescoping relation, the inner receptacle is formed with outwardly rounded projections 17 and 18 in the top and bottom, and the outer receptacle is formed with corresponding depressions 19 and 20 on the inside of the top and bottom respectively, forming cooperating bearings 85 and contacting surfaces between the two receptacles. The bottom of the inner receptacle is formed with an inwardly dished portion 21 of the same or greater depth than the projection 18 thereof, so that the latter will not project below the outer edge of the bottom of the part 8 and the latter will rest flatly upon its outer edge when taken out of the outer receptacle and placed upon a plain surface.

To permit a yielding tilting of the inner receptacle with respect to the outer one, the top and bottom of the outer receptacle are conically indented from the outside to form depressions 21' and 22, from which the de-

pressions 19 and 20, which form the bearings for the inner receptacle, are depressed in the opposite direction. These bearing depressions 19 and 20 are less in height than the depressions of the container parts, so that the outside container will rest flatly upon its upper or lower edges.

With this construction, it is obvious that the cooperating bearing projections and depressions of the receptacles will permit a limited tilting upon jar of the inner receptacle in any direction, and as the bearing engagement is between rounded surfaces, the inner receptacle is rotatable within the outer one. 10 The parts being made of sheet metal have certain inherent resilience, so that by properly proportioning the receptacles the cover of the inner one is engaged when the cover of the outer receptacle is placed in position, 15 and the rotative movement of the outer cover parts engaging and tightening the bayonet joints in the inclined portions thereof will cause a resilient compression of all of the receptacle parts, yieldingly binding them all 20 together and holding a watch movement, for example, tightly in place within the inner receptacle.

It is thought that this invention and many of its attendant advantages will be understood from the foregoing description, and it will be apparent that many changes may be made in the form, construction and arrangement of the parts without departing from the spirit and scope of the invention or sacrificing all of its material advantages, the form hereinbefore described being merely a preferred embodiment thereof.

I claim:

- 40 1. A shipping container comprising a pair of two piece boxes, one fitting within the other and engaged thereby, the boxes having walls with cooperating depressions and projections for mounting the inner box for rotating and tilting movement in the outer one.
- 45 2. A container comprising a pair of two piece receptacles, one fitting within the other, the parts of each receptacle fitting one within the other, and the outer receptacle having yielding top and bottom walls to hold the inner container parts together, each receptacle as an entirety from the other, the lower parts of the outer receptacle being bent inwardly and upwardly to form a bottom which engages the bottom of the inner receptacle, and a bayonet joint in the walls of the outer receptacle for holding the inner container between the outer yielding walls.
- 55 3. A shipping container comprising inner and outer telescoping receptacles having corresponding opposite projections in their tops and bottoms, the top and bottom of the outer receptacle, being yieldable, and the side walls being rigid and having reinforcing peripheral beads and connected to press the tops and

bottoms of the receptacles in yielding engagement with each other.

4. The combination of a pair of telescoping receptacles fitting one within the other and having oppositely engaging tops and bottoms, the top and bottom of each receptacle fitting one within the other and the top and bottom of the outer receptacle being bent inwardly to have central separable engagements with the top and bottom of the inner receptacle, the parts of the outer receptacle being formed with a tightening bayonet joint for holding the receptacles together and each receptacle being separable as an entirety from the other.

5. The combination of a pair of telescoping receptacles fitting one within the other, the inner receptacle having outward projections at the top and bottom, and the other receptacle having corresponding projections at the inside of the top and bottom for receiving the projections of the other receptacle and permitting a resisted tilting and rotative movement of the latter, and fastening means in the telescoping walls of the outer receptacle for clamping the parts thereof together and holding the receptacles in engagement with each other.

6. A shipping container for a watch movement, comprising a pair of telescoping receptacles fitting one within the other, the top and bottom parts of the inner receptacle being adapted to engage and to hold a watch movement in place therebetween and having outward projections at the top and bottom, the outer receptacle having depressions in the top and bottom to receive the said projections of the inner receptacle and permitting a rotative and tilting movement of the latter in the outer receptacle, and tightening bayonet joints between the telescoping parts of the outer receptacle for holding the inner receptacle engaged between the depressions of the top and bottom of the outer receptacle.

7. A container for watch movements, comprising a pair of telescoping covered receptacles to fit one within the other, the inner receptacle having cooperating parts to engage the edge of and hold a watch movement in position therebetween when the cover and bottom are placed together, the outer container having a resilient top and bottom for engaging corresponding opposite parts of the inner receptacle but permitting a limited tilting movement of the latter therein, and inclined bayonet slots in the telescoping walls of the outer receptacle for pressing and holding the outer receptacle in yielding engagement with the inner receptacle.

8. A container for a watch movement, comprising a pair of independently covered receptacles fitting one within the other, the inner receptacle having cooperating top and bottom parts to engage the edge of a watch movement therebetween when they are placed

together, with notches in the edges through which a watch stem may protrude, the outer receptacle having yielding top and bottom walls for engaging the top and bottom of the inner receptacle and having reinforced telescoping sides with inclined bayonet joints therein for drawing the outer receptacle parts together and thereby yieldingly clamping the inner receptacle in position therebetween.

10 9. A double container, comprising inner and outer covered receptacles telescoping at their edges and having resiliently engaging corresponding parts at the centers of their tops and bottoms, the outer receptacle having interengaging parts in the edges, and the inner receptacle having its sides formed to fit one within the other and to engage an article between the edges thereof and being separable with its cover from the cover of the

20 outer receptacle.

10. A double container, comprising inner and outer receptacles with telescoping edges and resilient top and bottom sides, and with corresponding mutually engaging projections 25 and depressions in their tops and bottoms to permit a limited tilting movement of the receptacles.
